(57) **CLAIM**

The ornamental design for a portable computer, as shown and described.

DESCRIPTION

FIG. 1 is a front, left side and top perspective view of a portable computer showing our new design; FIG. 2 is a rear, right side and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view taken from detailed circle 9 in FIG. 1;

FIG. 10 is an enlarged view taken from detailed circle 10 in FIG. 1;

FIG. 11 is an enlarged view taken from detailed circle 11 in FIG. 2;

FIG. 12 is a front, left and top perspective view thereof of the portable computer of FIGS. 1-11 in a closed configuration; and,

FIG. 13 is a rear, right and bottom perspective view thereof of the portable computer of FIGS. 1-12 in a closed configuration.

The dash-dash broken lines in the drawings depict the portions of the portable computer that form no part of the claimed design.

(Continued)

The dot-dash broken lines in the drawings represent the extents of the enlarged detail views and form no part of the claimed design.

1 Claim, 13 Drawing Sheets
